TOY BUILDING BLOCK SET

Wilbert E. Schauer, Milwaukee, Wis., assignor to
 The Mueller & Son Company, Milwaukee, Wis.,
 a corporation of Wisconsin

Application October 4, 1935, Serial No. 43,472

9 Claims. (Cl. 46—19)

This invention relates to improvements in toy building block sets.

It is the primary object of the invention to provide a novel and improved toy building block

- 5 set combining the features of a jigsaw puzzle with those of a set of building units and adapted to be assembled in a particular sequence to produce a specific building structure, the blocks also being adapted to be assembled in an entirely different
 10 manner in any desired arrangement to produce a multiplicity of other structures through an entirely different connection between blocks.

More specifically, I propose by means of the present invention to provide a building whereof
 15 the sides and roof are fashioned of separate strips depending for their position entirely upon a frictional interlock effected solely at their ends. Each of the major strips comprising the set is notched at its end to have the form of an elongated H. The notches are preferably, however,
 20 offset from the center line so that the terminal lug on one side of the notch is thicker than the terminal lug on the other, to tend to require the assembly of the strips in their proper relation.

25 Moreover, the width of the thick lug and the thin lug of each strip combined is equal to the width of the notch, so that when the strips are properly assembled the thick lug of one and the thin lug of the next adjacent strip are received together in interlocking engagement in the notch of an adjacent strip in a contiguous wall surface. The width of the aforesaid notches is also equal to the thickness of the strips to make it possible to assemble them in the formation of many
 30 structures other than the building design for which they are primarily adapted.

All of the several strips are preferably patterned with a surface marking either printed thereon or stamped therein, or formed in relief
 40 upon their faces. These surface markings are such as to make it immediately evident when one strip is out of place so that in the correct assembly of the primary structure there will be but one place for every given strip, which must be
 45 in its place in order that the structure will appear correct when assembled.

It is a further object of the invention to provide a novel and improved form of assembled roof in which the eave portions of the ends of the roof are substantially continuous from the ridge downwardly, each being notched for engagement with the ridge and notched to receive the terminal lugs of the several longitudinal strips comprising the intermediate portion of roof.

In the drawings:

Figure 1 is a view in perspective of a completed building structure comprising the building block sets of this invention.

Figure 2 is an "exploded" view showing in perspective typical component parts of the building block sets as they appear in slightly separated positions.

Figure 3 is a fragmentary detail in perspective showing the corner interlock between unmarked strips comprising the building.

Figure 4 is a fragmentary detail view in perspective showing another manner of connecting the strips.

Figure 5 is a fragmentary detail view in perspective showing a further optional manner of connecting the strips.

Figure 6 is a view similar to Figure 3 showing in fragmentary detail in perspective a modified type of building block unit provided with a modified surface marking to represent a brick rather than a log structure.

Like parts are identified by the same reference characters throughout the several views.

The great majority of the building blocks used to construct the building shown in Fig. 1, are of the form designated by reference character 1. Assuming that the structure shown in Fig. 1 is secure, it will be obvious that the strips 1 comprising the ends and front and back thereof will be of uniform length. Each comprises a thin strip of wood having notches 8 at its ends defining terminal lugs 9 and 10 which are respectively thick and thin, the notches being offset slightly from the longitudinal center line of the stick. Although each notch 8 is preferably offset, its thickness is exactly half the width of the stick so as to be substantially equal to the combined width of the tongues 9 and 10. Thus the several sticks may be interlocked as shown in Fig. 3 with the adjacent sticks 1 of one wall having their adjacent lugs 9 and 10 each engaged in one of the notches 8 of an adjacent stick in the contiguous wall.

The thickness of each strip 1 is preferably exactly half of its width. Thus the thickness of each strip corresponds substantially identically to the width of the notch 8. The depth of the notch, in turn, is preferably exactly equal to the width of the stick. Thus the full width of one stick may be received edgewise into the notch of another stick as shown in Fig. 4, the parts being held frictionally in any relative position in which they may be assembled in this manner.

Likewise, the notched end portions of two

sticks at right angles to each other may be interlockingly engaged as shown in Fig. 5, to make an extremely rigid joint connecting two sticks end to end. By means of these two types of connection the most elaborate skeleton structures may be assembled. If desired, the lugs 9 and 10 may be made only half as long as those shown in Figs. 1 to 5 inclusive, and in that case the sticks may be provided with a surface configuration suggestive of brick as shown in Fig. 6, where the sticks 7' are interlocked in the same manner as Fig. 3 except that the lugs 9 and 10 do not project from the mortised corners.

Where the mortised corners project, as best shown in Figs. 1 and 3, the sticks preferably have a surface configuration or marking suggestive of the logs of a log cabin. Preferably, the surfaces of the sticks will be free of relief and parallel and the desired appearance will be produced by printing a surface design on to the sticks. The windows 14 and the door 15 of the building shown in Fig. 1 were made by stamping or printing an appropriate design on to the successive sticks employed in the building of the structure. The back surfaces may have different designs or may be left unfinished to increase the co-efficient of friction.

It will also be noted that there is a carefully worked out series of shadows or shading at 16. These shadows are carried across the several consecutive sticks comprising the building, so that if a child using the toy assembles any stick in the wrong location the error will immediately be apparent. There is but one location for every stick in which the design on the surface thereof will match the design on adjacent sticks. This fact adds greatly to the interest of the set of blocks when the blocks are assembled in the form shown in Fig. 1.

40 Interlocking with the sticks 7 comprising the front, back and end walls of the building structure shown in Fig. 1, are gable units such as that shown at 17 in Figs. 1 and 2. For convenience each gable unit comprises a single piece of wood having beveled margins 18 coming to a peak at 19. Each gable unit also has notches 8 exactly like those of the sticks 7 to complete the assembly of the end wall.

A ridge unit at 20 comprises two of the sticks 50 7 which have been beveled and nailed to an underlying ridge board 21 which holds them together as a unit. The bevel of strip 7 is such that they will fit the peaks 19 of the gable unit, as is fully apparent from Fig. 2. With the ridge unit 55 20 in place, the eaves strips 23 may be interlocked therewith. Each of the eave strips has a piece of molding at 24 depending from its margin, and each is provided with a series of lugs at 25 with which the several sticks 7 used to comprise 60 the body of the roof, may be interlocked.

The strips 7 used in the roof, are identical, except in surface marking, with the strips used in the walls. The chimney 26 is simply an appropriately shaped block of wood formed to fit over the 65 ridge.

The building specifically illustrated, by way of example, may readily be converted into other buildings of desired form. For example, one wall of this building may be omitted entirely and, if 70 desired, it may be replaced by a notched strip such as that used at 23 to comprise the eaves of the roof. Such a strip will interlock the ends of the adjacent wall boards and may resemble a corner post or equivalent structural member adjacent 75 the open side of the shed thus formed.

I claim:

1. A building block comprising an elongated strip provided with terminal tongues and an intervening notch, the width of the notch being approximately equal to the combined width of 5 both tongues, whereby the tongues of two corresponding building blocks may be engaged simultaneously in said notch to be frictionally retained between the first mentioned tongues.

2. A building block comprising an elongated 10 strip notched at each end to provide pairs of terminal tongues substantially aligned with the margins of the strip, the width of each notch being substantially equal to the thickness of the strip and to the combined width of the tongues 15 at either side thereof, whereby said notch is adapted to receive and frictionally retain other tongues aligned with the opposite margins of two similar blocks.

3. A building block comprising an elongated 20 strip, the width being approximately twice the thickness and the length many times exceeding its width, and provided at each of its ends with notches approximately equal in depth to the width of strip and equal in width to the thickness 25 thereof, and tongues at each side of the respective notches, each pair of tongues having a combined width substantially equal to the intervening notch and the thickness of the strip, two superposed tongues of two like blocks being 30 together receivable for frictional retention in one of the notches aforesaid.

4. A building block comprising a strip of elongated form having a terminal notch slightly off center with respect to the center line of the 35 strip and providing tongues of unequal thickness at either side of the notch, the combined thickness of said tongues being substantially identical with the width of the notch, whereby the thicker and thinner tongues of blocks identical with 40 the block aforesaid may be conjointly received for frictional retention in said notch.

5. In a structure of the character described, a pair of continuous walls each comprising similar strips notched at their adjacent ends to provide spaced tongues, the notched portion of each strip being frictionally engaged with the tongues of two consecutive strips in the contiguous wall, whereby the strips of each wall interlockingly 45 secure together the strips of the other of said 50 walls.

6. A building structure comprising a series of strips in substantial edge contact to comprise each wall of the structure, the ends of said strips being interlocked at the corners between 55 contiguous walls, and each strip having terminal tongues and an intervening notch, the tongues being engaged in the notches of two consecutive strips in an adjacent wall, and the notch of each strip receiving adjacent tongue portions of said 60 two consecutive strips in the contiguous wall.

7. A building structure comprising walls and roof panels, each including identical building blocks, each said block comprising an elongated strip approximately the length of a wall of said building and notched at its ends to provide two pairs of oppositely projecting terminal tongues whereof the combined thickness is approximately equal to the width of the intervening notches, the strips comprising contiguous wall 70 panels being mutually offset, two adjacent terminal tongues of consecutive strips in one panel being engaged in the notch of a staggered strip in an adjacent wall panel.

8. A building structure comprising a plurality 75

of walls each including elongated building strips in interlocking frictional engagement at the corners of said walls, gable pieces mounted on opposing walls and having means interlocking 5 with a strip of an intervening wall, a ridge member spanning said gable pieces, strips substantially identical with those of the walls spanning said gable members, and eaves units having means interlocked with the ends of said last 10 mentioned strips and with said ridge unit, whereby to hold said last mentioned strips upon said gable members as a roof for the structure.

9. In a building structure, the combination

with wall devices having peaked gable members at their tops, of a pair of ridge boards provided with means connecting them together to span the apices of said gable peaks, eaves units provided with means interlockingly engaging their 5 respective ends with said ridge members, each of said eaves units having its inner side margin provided with notches and a series of strips spanning said gable members and having tongues interlockingly engaged in the notches of said 10 eaves units, whereby they are maintained in assembly to comprise a roof structure.

WILBERT E. SCHAUER.

CERTIFICATE OF CORRECTION.

Patent No. 2,088,874.

August 3, 1937.

WILBERT E. SCHAUER.

It is hereby certified that error appears in the printed specification of the above numbered patent requiring correction as follows: Page 2, second column, line 44, claim 5, for the word "continuous" read contiguous; and that the said Letters Patent should be read with this correction therein that the same may conform to the record of the case in the Patent Office.

Signed and sealed this 5th day of October, A. D. 1937.

Henry Van Arsdale
